REMOTE-CONTROL SYSTEM

Harry G. Evers, Newark, N. J., assignor to Automatic Electric Laboratories, Inc., Chicago, Ill., a corporation of Delaware

Original application August 21, 1944, Serial No. 550,362. Divided and this application November 7, 1945, Serial No. 627,260

9 Claims. (Cl. 177—380)

1

The present invention relates in general to code transmitters and particularly to a code transmitter for a remote control system which employs a plurality of signaling channels to control a multiplicity of functions at a number of remote stations either simultaneously or selectively.

The present case is a division of my copending application, Serial No. 550,362; filed August 21, 1944; entitled Remote control systems.

The disclosure illustrating one embodiment of the invention is used to control the operation of three aircraft, selectively or simultaneously, from a fourth control aircraft by means of a radio frequency carrier upon which ten audio frequency signaling tones may be superimposed. It is to be understood that the invention is not limited to the control of aircraft as it will be apparent that it is readily adapted to the control of other moving vehicles or stationary equipment either by means of the radio link illustrated or by wire lines.

The principal object of the present invention is to provide a code sender that is capable of transmitting a multiplicity of codes at a rapid rate through the efficient use of a plurality of signaling channels, but without requiring the use of more than one channel at a time.

A further object of the invention is to provide a code sender having code selecting means that is common to a plurality of groups of control keys each of which controls a separate function.

Another object is to provide means for allowing preferential use of the code selecting means by certain of the groups of control keys.

Still another object is to provide a novel arrangement for transmitting codes in sequence when the key operations overlap.

A still further object is to provide a novel method of initiating the operation of the code sender in response to the operation of a control key.

Other objects of the invention will appear upon a further perusal of the specification and the accompanying drawings, in which:

Figs. 1, 2 and 3, when placed side by side in the order named, comprise a schematic diagram of the switching equipment employed in the control plane.

As previously mentioned, ten audio frequency tones, any one of which may be superimposed on a radio frequency carrier, are employed to control three airplanes simultaneously or selectively. Four of these tones are used for directing the controlled planes up, down, right, or left. Two

2

more of the tones are used for increasing or decreasing any one of ten variable functions previously selected by the switching equipment as will presently be described. The remaining four tones are used for the control of the switching equipment constituting the invention. Of the latter four tones, one is used to control a group of distributor relays in the controlled plane, and each of the other three tones controls a group of register relays in conjunction with the distributor relays. Each control signal consists of a seizure pulse of one of these three tones followed by five pulses of the tone which controls the distributor relays. During none, or any one or two, of the four spaces between the five pulses the same tone used for seizure may be repeated. The distributor relays prepare a circuit to a different one of four relays in the register corresponding to the seizure tone during each of the four spaces between the five tone pulses. When the seizure tone is repeated during these spaces the corresponding relays in the register are operated. The various combinations which can be formed by operating none, or any one or two, of the four relays permits ten functions to be controlled by a register.

In the first register four of the ten possible functions are used for plane selection and two more are used for aileron control. The second register is used for controlling five apparatus units, each of which has two possible operated conditions. The ten possible combinations in the third register are used to prepare any two of twenty circuits associated with ten apparatus units. Either one of the two selected circuits may then be completed for as long an interval as desired by the increase or decrease tone to turn on or off, or to increase or decrease the degree of operation of, the selected one of the ten apparatus units.

The coded signals are produced in the control equipment by a relay type code sender and a group of ten code selecting relays. A group of control keys, or switches, is provided for each group of functions. Each key in a group corresponds to one of the code selecting relays so that the code transmitted depends upon which key in a group is operated. The same codes are used by all groups but the particular one of the three tones used for seizure and function selection depends upon the group in which a key is operated. This latter tone selection is accomplished by two relay groups, each of which is associated with one of the key groups. These latter relay groups also cause signals to be transmitted in

sequence when keys in different groups are operated at nearly the same time, and also connect the code selecting relays to the key group in which a key has been operated in order to select the code to be transmitted.

The function of each unit will now be described with reference to the accompanying drawings. In Fig. 1 the ten keys C1 to C10 which control the ten variable functions are shown at the top of the drawing. These keys are of the mechanical interlocking type in which the operation of any key releases a previously operated key and latches itself operated. A set of common springs C11 are also provided and are arranged to be momentarily operated by the latching bar when any of the selecting keys is operated. The group of four keys A1 to A4 at the left center portion of the drawing is used for plane selection. These keys are also of the mechanical interlocking type and common springs A5 are also provided for this group. At the lower left there is shown the increase-decrease key 10 and the quadrant switch 20. The quadrant switch consists of a shaft that is flexibly mounted near one end so as to normally occupy a vertical position, but permitting its free end to be displaced forward, backward, or laterally in the same fashion as the control stick in an airplane. Four snap-actuation switches are positioned about the shaft at 90° intervals so as to permit selective operation of any one of the switches by movement of the free end of the shaft. The forward and backward motion of the quadrant switch operates the elevators of the controlled planes, while the lateral motion of the quadrant switch controls the rudders, either alone or in conjunction with the ailerons depending upon whether a switch 21 located within the shaft of the quadrant switch is operated or released. Two ordinary relays, 100 and 110, and two mechanically interlocked relays, 120 and 130, are controlled by switch 21 to accomplish this result in a manner to be described presently. Relays 140 to 160 are storage relays associated with the plane selection key group, and relays 170 to 190 are similar storage relays associated with the variable function selecting key group.

In Fig. 2 five single pole double throw toggle switches B1 to B5 are shown at the top of the drawing. Each toggle switch is associated with a pair of mechanically interlocked relays like 200B and 210B. Each of these mechanical interlocking relays is in turn associated with one of the ten code selecting relays 200 to 290 shown at the center of the drawing. Relay 200T shown at the left transfers the code selecting relays from the mechanically interlocked relays to contacts of the storage relays 160 and 190 of Fig. 1 when one of the mechanically interlocking push keys of Fig. 1 is operated. The three remaining relays 210S to 230S at the right of the drawing are start and lockout relays which start the code sender of Fig. 3 whenever one of the code selecting relays is operated and also prevent any new codes from being registered until a previously registered code has been transmitted.

The relays shown in Fig. 3 constituting the code sender consist of a pair of pulse generating relays 300 and 310, a pulse directing relay 320, and five counting relays 330 to 370. At the right of the drawing a radio transmitter and ten audio frequency oscillators are illustrated in block form. It should be noted that although ten separate oscillators have been illustrated for convenience, a single oscillator will suffice if it is arranged so that its frequency is controlled by

the switching equipment. This is possible because only a single frequency is required at a time and can readily be accomplished by using a conventional vacuum tube oscillator in which the frequency is determined by resistance and capacitance, or inductance and capacitance elements, by providing ten sets of frequency determining elements and connecting the proper set in the oscillating circuit by keying relays controlled over the leads which are shown terminating in oscillators OSC. 1 to OSC. 10.

Returning now to Fig. 1, the transmission of a signal to effect a plane selection will be described in detail. As previously mentioned, plane selection is accomplished by the four key strip of interlocking push keys A1 to A4. Assuming that it is desired to control plane 1 individually, key A1 will be operated. The operation of key A1 releases any previously operated key, momentarily operates the common springs A5, and prepares a circuit to code selecting relay 220 from + battery at contacts of relay 230S over lead 39, through operated contacts A1 to contacts of relay 160. The momentary operation of the common springs A5 completes a circuit to relay 140 causing it to operate and lock itself by its own make contacts. Relay 140 completes a circuit to relay 150 from + battery at contacts 211S, through contacts 221S, over lead 31, through contacts 141 and 181. This latter circuit will be completed only if the code selecting relays are free. If there is a code transmission in progress relays 210S and 220S will be operated and hence the circuit to relay 150 will not be completed until the previously registered code has been sent. When relay 150 operates it closes its locking circuit to contacts of relay 140, closes a circuit to relay 160, prepares a circuit for shunting down relay 140 over lead 32, and closes a circuit to relay 200T over lead 33. Relay 160 operates, prepares its locking circuit to lead 34, and connects all of the plane selecting keys, A1 to A4, to contacts of relay 200T. Relay 200T operates; prepares its locking circuit to contacts of relay 230S; prepares a circuit to OSC. 2 from contacts of the code selecting relays over lead 45, through contacts of relay 200T to lead 35, over lead 35 to contacts of relay 160, and thence over lead 36 to OSC. 2; and completes the connections from the plane selecting keys A1 to A4, to code selecting relays 220 to 250, respectively. A circuit is thus completed to relay 220 from + battery over lead 30 through contacts of key A1, contacts of relay 160, lead 37, contacts of relay 200T, through the winding of relay 220, through the chain contacts of the succeeding code selecting relays 230 to 290 to lead 38, and over lead 38 to - battery, or ground, at contacts of relay 330.

The purpose of the chain contacts in the circuit last traced is to prevent more than one code selecting relay from being operated at the same time. In the present case this serves as a precaution to prevent a false code from being transmitted if two of the interlocking push keys were operated at the same time by mistake. However, as will be later described, it is intended that several of the toggle switches, B1 to B5, may be operated at the same time and in that case the chain circuit causes the codes corresponding to each toggle switch operation to be sent in sequence.

Relay 220 operates over the previously traced circuit, prepares its locking circuit through relay 210S, closes a circuit to relay 230S, and connects lead 45 to lead 42 so as to operate OSC. 1

during the second spacing interval. Relay 230S operates, removes + battery from lead 30 thus opening the operating circuit to relay 220 and removing a short circuit from relay 210S, and completes the locking circuit for relay 200T. Relay 210S operates in series with relay 220 from + battery over lead 33, closes a circuit to relay 220S, closes a locking circuit to relay 160 over lead 34, removes + battery from lead 31 to guard the code selecting relays, and short-circuits relay 140 over lead 32. Relay 140 restores and opens the locking circuit to relay 150. Relay 150 restores and opens the operating circuits to relays 160 and 200T.

When relay 210S operated it also completed a circuit to OSC. 2 from ground at contacts 311 through contacts 371, over lead 39, through contacts 212S and thence over the previously traced circuit including leads 45, 35, and 36 to the oscillator. The operation of OSC. 2 modulates the radio frequency carrier produced by the transmitter at a particular audio frequency. The carrier is demodulated by the radio receiver in the controlled plane and the audio frequency signal causes a register therein to be seized.

The above operations complete the registration of the code to be transmitted and the seizure of a register in the controlled plane. The code transmission is started by the operation of relay 220S which extends + battery over lead 45 to the code sender. A circuit is closed to relay 310 from + battery on lead 46 causing it to operate and close a circuit to relay 300. Relay 300 operates and opens the circuit to relay 310. Relay 310 restores and opens the circuit to relay 300 which restores and recloses the circuit to relay 310. This cycle of operations is repeated five times for each transmission of a signal as determined by counting relays 330 to 370. The speed and the per cent closure time of the contacts of relay 310 is governed by the operate and release times of relays 300 and 310. Relay 310 is made slow-to-release by a copper sleeve on its core. Relay 300 is made slow-to-release by an adjustable shunting resistor. Relay 300 is also preferably made slightly slow to operate by using a relatively large number of turns in its winding in order to secure the optimum per cent closure time of the contacts of relay 310. During the first operation of relay 310, contacts 311 transfer ground from OSC. 2 to OSC. 1, and contacts 312 close a circuit to relay 370. Relay 370 operates, closes its locking circuit to lead 46, prepares circuits to relays 320 and 360 at contacts 372 and 373, and prepares a circuit for connecting ground to lead 41 through contacts 371 during the first restoration of relay 310. The first restoration of relay 310 grounds lead 41, closes a circuit to relay 320 through contacts 372, and opens the operating circuit to relay 370. Relay 320 operates, closes its locking circuit through contacts 372, and prepares a circuit to relay 360 through contacts 373. The second operation of relay 310 completes a circuit to relay 360 at contacts 312, transfers ground from lead 41 to OSC. 1, and closes a further circuit to relay 320. Relay 360 operates, closes its locking circuit, prepares a circuit to relay 350, opens the operating circuit to relay 320, and prepares a circuit to ground lead 42 during the second restoration of relay 310. When relay 310 restores the second time it opens the locking circuit to relay 320, opens the operating circuit to relay 360, and grounds lead 42 which causes the operation of OSC. 2 since lead 42 is connected to lead 45 by code selecting relay

220. Subsequent operations and restorations of relay 310 cause the successive operations of counting relays 350, 340 and 330 in conjunction with the operation of relay 320. OSC. 1 is operated during each operation of relay 310 and leads 43 and 44 are grounded during the successive restorations of relay 310. When relay 330 operates upon the fifth operation of relay 310 it removes + battery from lead 38 to release relays 220 and 210S, opens the locking circuit to counting relays 340 to 370, closes its own locking circuit, and connects + battery from operated contacts on relay 310 to lead 46 to hold relay 220S when relay 210S restores. Relays 340 to 310 restore. Relay 220 restores and opens the circuit to relay 230S. Relay 210S restores, opens the operating circuit to relay 220S, and opens the locking circuit to relay 160. Relay 160 restores. Relay 310 restores, opens the circuit to relay 300, and opens the locking circuits to relays 220S and 330. Relay 330 restores. Relay 220S restores after its slow release period and connects + battery to lead 31 to enable a new registration to be made.

25 The operation of the code sender interrupted the operation of OSC. 2 and caused five successive operations of OSC. 1. OSC. 2 was reoperated during the second spacing interval between the five pulses. If plane selecting key A2 is operated a similar cycle of operations occurs except that code selecting relay 230 will be operated instead of relay 220 causing OSC. 2 to be operated during the third spacing interval instead of the second. Similarly, when plane selecting key A3 is operated, code selecting relay 240 will be operated instead of relay 220 causing OSC. 2 to be operated during the fourth spacing interval instead of the second. Plane selecting key A4 is operated when it is desired to control all three planes simultaneously. The operations are again similar to those previously described, in this case code selecting relay 250 is operated to cause OSC. 2 to be operated during both the first and second spacing intervals. The manner in which these codes are employed to effect the desired plane selection is fully described in the afore-mentioned copending application.

When the quadrant switch 20 is moved forward or backward either OSC. 9 or 10 is operated over leads 48 or 47 to cause the elevators in the selected plane to be operated accordingly. In a similar manner, lateral movement of the quadrant switch operates OSC. 5 or OSC. 6 over leads 50 or 49 to cause either the rudder alone, or both the rudder and ailerons, in the selected plane to be operated accordingly. Normally the rudder and ailerons are operated jointly to cause the plane to bank when a turn is executed. In landing operations, switch 21 is operated to prevent banking when the quadrant switch is moved laterally. The transmission of a code signal to effect this result is similar to the transmission of a plane selection signal except for the manner of registering the code in response to the operation or release of switch 21. When switch 21 is operated it locks mechanically and closes a circuit to the upper winding of relay 100. Relay 100 operates, closes a circuit to relay 140, closes a circuit to relay 140 from + battery at contacts 161 through contacts 161 and contacts of relay 120, and prepares a circuit for operating code selecting relay 200 from + battery over lead 66 and through contacts of relay 120. Relay 110 operates, prepares its locking circuit, and disconnects leads 49 and 50 from the quadrant switch to pre-

vent any operation of the rudder in the controlled plane while the signal is being transmitted. Relay 140 operates and closes a circuit to relay 150 from + battery on lead 31 if or when the code selecting relays are free. The succeeding operations of relays 150, 160, code selecting relay 200, etc. are the same as previously described. In addition to the operations described previously the operation of relay 160 opens the operating circuit to relay 140 and closes the locking circuit to relay 110 at contacts 161. The operation of relay 210S and subsequent release of relays 140 and 150 closes a circuit to relay 130 and to the lower winding of relay 100 from + battery over lead 32, through contacts of relay 150 to lead 67, through contacts of relay 200 to lead 68, and through contacts of relays 160 and 100. The above circuit to the lower winding of relay 100 is to prevent relay 100 from being released by the opening of switch 21 during the signal transmission. Relay 130 operates and mechanically releases relay 120. Relay 120 restores, mechanically locks relay 130 operated, and opens the operating circuit to relay 110. When the code signal has been sent as described for the plane selecting operation relays 200 and 210S are released by the operation of relay 330 thus removing + battery from lead 68. Relay 100 remains operated as long as the circuit to its upper winding is maintained by switch 21. Relay 130 is deenergized but is mechanically locked in the operated position by relay 120. The release of relay 210S also removes + battery from lead 34 which releases relay 160. Relay 160 restores and unlocks relay 110 at contacts 161. Relay 110 restores and connects leads 49 and 50 to the quadrant switch. Since none of the leads 41 to 44 are connected to lead 45 by code selecting relay 200 the code transmitted consists of one operation of OSC. 2 followed by five operations of OSC. 1.

When it is desired to return to combined control of rudder and ailerons by the quadrant switch so as to execute banked turns, switch 21 is mechanically released to open the circuit to the upper winding of relay 100. Relay 100 restores, closes a circuit to relay 110, closes a circuit to relay 140 from + battery at contacts 161, through contacts 161 and contacts of relay 130, prepares a circuit to operate relay 120 from lead 68, and prepares a circuit to operate code selecting relay 210 from lead 66. Relays 110, 140, etc. operate as before. This time when + battery is connected to lead 68 a circuit is closed to relay 120 through back contacts of relay 100 and operated contacts of relay 130. Relay 120 operates, opens the operating circuit to relay 110, and mechanically releases relay 130. Relay 130 restores, mechanically locks relay 120 operated, and opens the operating circuit to relay 120. Relay 110 is released when relay 160 restores at the end of the transmission and it reconnects leads 59 and 50 to the quadrant switch. As code selecting relay 210 connects lead 41 to lead 45 the transmitted code signal will consist of one operation of OSC. 2 followed by five operations of OSC. 1 with OSC. 2 reoperated during the first spacing interval.

The operation of the variable function selecting operations of keys C1 to C10 is very similar to the plane selecting operations by keys A1 to A4. A separate start signal register is used comprising relays 170 to 190, each of which controls circuits corresponding to those controlled by the start signal register relays 140 to 160, respectively, associated with the plane selecting

keys. Relay 170 is operated by the momentary operation of the common springs C11 whenever one of the keys C1 to C10 is operated to the latching position. Relay 180 is then operated over lead 31 when the code selecting relays are free. However if relay 140 is operated, indicating that a key in the plane selecting group has been operated and the corresponding code signal has not yet been transmitted, contacts 141 of relay 140 prepare a circuit to relay 150 and prevent the operation of relay 170 until this plane selecting code has been registered and transmitted. The plane selecting keys are thus given preference because in using the control equipment the function selecting key may often-times be operated immediately after the operation of the plane selecting key corresponding to the plane in which the function is to be performed. When relay 180 does operate it closes a circuit to relay 190 which operates and connects all of the keys C1 to C10 to the corresponding code selecting relays, 200 to 290, through contacts of relay 290T, which is also operated by relay 180 over lead 33. The registration and transmission of the code signals is the same as described for plane selection except that a greater number of codes are used and also that OSC. 4 takes the place of OSC. 2. This selection is accomplished by the operation of relay 190 in place of relay 160, thus connecting lead 35 to lead 69 in place of lead 36. Therefore, the first pulse of ground over lead 35 causes the operation of OSC. 4 which causes the seizure of a corresponding register in the controlled planes. At the conclusion of a code signal the relays in the seized register will be operated in accordance with the operations of OSC. 4 during the spacing intervals, which operations are controlled by the connections of leads 41 to 44 to lead 45 by the code selecting relays. The complete code used is tabulated below, the crosses indicating the spacing intervals during which OSC. 4 is operated.

Selected Function	Spacing Interval			
	1	2	3	4
1				
2		X		
3			X	
4				X
5				
6		X	X	
7	X		X	
8	X			X
9		X	X	
10		X		X

The above code is the same as that used for plane selection and aileron control except that OSC. 2 was used then instead of OSC. 4. The registers in the controlled planes which are associated with OSC. 4 are arranged to select any one of ten pairs of circuits. Either circuit of a selected pair may be completed by throwing key 13 to the right or left to operate OSC. 7 or 8 over leads 76 or 77. As either one of the selected circuits may be completed for as long an interval as desired they are suitable for the control of continuously variable functions, such as the engine throttle.

The transmission of code signals in response to the operation of one or more of the toggle switches B1 to B5 is considerably different than that heretofore described as regards the registration upon the code selecting relays. For one thing, it is intended that a number of these switches may be operated simultaneously or in rapid succession

and that the corresponding codes shall then be transmitted in succession. It is also intended that these switches may be operated while the transmission of a code due to the operation of a key in one of the other groups is in progress. Assuming that switch B1 is thrown to the right, a circuit is closed from + battery over lead 31, through chain contacts on relays 140 and 170, over lead 78, through switch B1, contacts of relay 200B, and contacts of relay 200T to code selecting relay 210. If the code selecting relays are in use this circuit will be open at contacts 211S and 221S. If one of the keys in the other groups has been operated and has not yet been registered the circuit will also be open at contacts of relay 140 or 170. In the latter case the circuit will not be completed until the code selecting relays become free, the code corresponding to the operated key in the other key groups has been registered and transmitted, and the code selecting relays again become free. When the circuit is completed, relay 210 operates, prepares its locking circuit through relay 210S, closes a circuit to relay 230S, and closes a circuit to relay 210B in multiple with itself. Relay 230S operates. Relay 210B operates and mechanically releases relay 200B. Relay 200B restores and opens the operating circuit to relay 210 which also removes a short circuit from relay 210S. Relay 210S operates, closes a circuit to relay 220S and removes + battery from lead 31 to guard the code selecting relays and also opening the circuit to relay 210B. The code signal is transmitted as previously described except that OSC. 3 takes the place of OSC. 2. This occurs because lead 45 is connected through back contacts of relay 200T to lead 79 and relay 200T is not operated at this time. The transmitted code thus consists of one operation of OSC. 3 followed by five operations of OSC. 1 and a second operation of OSC. 3 during the first spacing interval. When switch B1 is returned to the left it closes a circuit to code selecting relay 200 from lead 78, through switch B1, and contacts of relay 200B after any previously stored signals have been transmitted. Relay 200 operates, prepares its locking circuit through relay 210S, closes a circuit to relay 230S, and closes a circuit to relay 200B in multiple with itself. Relay 230S operates. Relay 200B operates, mechanically releases relay 210B, and opens the operating circuit to relay 200 which also removes a short circuit from relay 210S. Relay 210B restores and mechanically locks relay 220B operated. Relay 210S operates and removes + battery from lead 78 by opening lead 31 at contacts 211S. The succeeding operations will not be described as they should be apparent from the preceding description.

If all of the switches, B1 to B5, were operated to the right simultaneously, a circuit would be completed to relays 210, 230, 250, 270, and 290 in multiple. All of these relays would attempt to operate but the operation of any one of them opens the circuit to all of the preceding code selecting relays by means of the chain circuit connected to lead 38. Consequently, only the highest numbered code selecting relay will remain operated, in this case relay 290. The operation of relay 290 causes the operation of relay 290B, which mechanically releases relay 280B and this in turn removes the short circuit from relay 210S which removes + battery from lead 31 to guard the code selecting relays and starts the code transmission. After this first code has been sent

relay 210S is released and + battery is again connected to lead 31. If none of the push keys C1 to C10 or A1 to A4 have been operated in the meantime this + battery is extended to lead 78 causing code selecting relays 210, 230, 250, and 270 to again attempt to operate. This time relay 270 is the only relay which can remain operated. This cycle of operations is continued until the five codes corresponding to the operation of switches B1 to B5 to the right have been transmitted in succession. If any of the push keys is operated during the transmission of these five codes relay 140 or 170 will be operated and will extend lead 31 to relay 150 or 180 instead of to lead 78 thus causing the code corresponding to the operated push key to be registered and transmitted as soon as the code transmission in progress is completed. The transmission of the remaining codes corresponding to the operations of switches B1 to B5 will then be resumed where it was left off. Of course, some of the switches B1 to B5 may be operated to the left at the same time that others are operated to the right, the description being limited to operations in one direction merely for simplicity.

Having described and illustrated the invention, what is considered new and is desired to secure by Letters Patent is pointed out in the subjoined claims.

30. What is claimed is:

1. In a code signaling system, a normally inactive code sender adapted to produce a plurality of codes, a plurality of corresponding code selecting keys therefor having a common mechanical latching means arranged to release a previously operated key when any other key is operated to the latching position, switching means momentarily operated by said latching means in response to the operation of one of said keys, and means controlled by said switching means for initiating the operation of said code sender to produce code corresponding to such operated key.

2. In a code signaling system, a code sender, a plurality of groups of code selecting keys, each of said groups of keys having common mechanical latching means arranged to release a previously operated key when any other key in the group is operated to the latching position, switching means for each group momentarily operated by said latching means in response to the operation of one of the keys in the group, and means for each group controlled by said switching means for associating the code sender with the group in which a key is operated in response to such operation.

3. In combination, a plurality of circuits, a plurality of groups of keys, each of said groups of keys having common mechanical latching means arranged to release a previously operated key when any other key in the group is operated to the latching position, switching means for each group momentarily operated by said latching means in response to the operation of one of the keys in the group, and means controlled by said switching means for connecting said plurality of circuits to the group in which a key is operated in response to such operation whereby one of said circuits is completed by the operated key.

70. 4. In a code signaling system, a code sender, two groups of code selecting keys therefor, said code sender being adapted to transmit different codes successively in response to the simultaneous or overlapping operation of a plurality of control keys in one of said groups, and means re-

sponsive to the operation of a key in the other of said groups during said transmission for interrupting the transmission at the completion of the code in progress and for causing the code sender to transmit the code corresponding to the operated key in said other group, said means responding to the completion of said last code to cause the code sender to continue the interrupted transmission.

5. In a code signaling system, a code sender and a register, a two-position switch, a pair of mechanically interlocked relays, a second pair of relays in said register, two circuit paths each extending from a contact of the switch through contacts of said mechanically interlocked relays to one of said second pair of relays, and operating circuits for each of said mechanically interlocked relays including contacts of the second pair of relays, said circuits being arranged so that alternate operation of the switch between said two positions causes a momentary operating circuit to be closed to alternate ones of said second pair of relays in response to each switch operation, to thereby operate said last relays, said code sender controlled by the operation of said second relays for sending the code associated with each one of said second relays.

6. In a code signaling system, a code sender and a register, a pair of mechanically interlocked relays in said register, a second pair of relays, two circuit paths each extending through contacts of said mechanically interlocked relays to one of said second pair of relays, operating circuits for each of said mechanically interlocked relays including contacts of the second pair of relays, and means for closing either of said two circuit paths, said relay contacts being arranged so that alternate closure of said two circuit paths causes a momentary operating circuit to be completed to alternate ones of said second pair of relays in response to each such closure, to thereby operate said last relays, said code sender controlled by the operation of said second relays for sending the code associated with each one of said second relays.

7. In a code signaling system, a code sender, a plurality of register relays, a plurality of pairs of mechanically interlocked relays, each of said mechanically interlocked relays being associated with one of said register relays, operating circuits for each of said mechanically interlocked relays including contacts of its associated register relay, selecting circuits for each of said register relays including normally closed chain contacts on all of the succeeding register relays and contacts on the mechanically interlocked relays, said selecting circuits being arranged in pairs, and

means for closing either of the selecting circuits of each pair, said relays being arranged so that the corresponding register relays are successively operated in a predetermined sequence in response to the simultaneous closure of a plurality of said selecting circuits, thereby marking said code sender for sending the code associated with each register relay operated.

8. A code sender for a selective signaling system comprising a chain of counting relays and impulsing means therefor, a plurality of code selecting keys, a pair of signal lines, and means responsive to the operation of one of said code selecting keys for causing said counting relays to be sequentially operated by said impulsing means and for connecting one of said signal lines to contacts of one or more of said counting relays, said impulsing means and said counting relays being arranged to transmit a series of impulses over the other signal line in synchronism with the impulsing means and to transmit one or more impulses having a predetermined chronological relation to the impulses of said series which is characteristic of the operated key over said one signal line.

9. A code sender for a selective signaling system comprising a chain of counting relays and impulsing means therefor, a plurality of groups of code selecting keys, a plurality of signal lines each corresponding to one of said groups, a common signal line, and means responsive to the operation of a code selecting key in one of said groups for causing said counting relays to be sequentially operated by said impulsing means and for associating the signal line corresponding to said one group with the counting relays, said impulsing means and said counting relays being arranged to transmit a series of impulses over the common signal line and to transmit one or more impulses having a predetermined chronological relation to the impulses of said series over the signal line associated with the counting relays.
